CLAIM

The ornamental design for an audio/video doorbell and door viewer, as shown and described.

DESCRIPTION

FIG. 1 is a front, top perspective view of an audio/video doorbell and door viewer according to the present design; FIG. 2 is a back, bottom perspective view thereof; FIG. 3 is a front elevation view thereof; FIG. 4 is a back elevation view thereof; FIG. 5 is a left-side elevation view thereof; FIG. 6 is a right-side elevation view thereof; FIG. 7 is a top plan view thereof; FIG. 8 is a bottom plan view thereof; FIG. 9 is a front, top perspective view of the design disclosed in an open position; FIG. 10 is a back, bottom perspective view thereof; FIG. 11 is a front elevation view thereof; FIG. 12 is a back elevation view thereof; FIG. 13 is a left-side elevation view thereof; FIG. 14 is a right-side elevation view thereof; FIG. 15 is a top plan view thereof; and, FIG. 16 is a bottom plan view thereof.

The dashed lines depict portions of the audio/video doorbell and door viewer that form no part of the claimed design.

1 Claim, 16 Drawing Sheets

Related U.S. Application Data

continuation-in-part of application No. 29/673,311, filed on Dec. 13, 2018, now Pat. No. Des. 889,300.
